UNITED STATES PATENT OFFICE.

FRED B. COREY, OF SCHENECTADY, NEW YORK, ASSIGNOR TO GENERAL ELECTRIC COMPANY,
A CORPORATION OF NEW YORK.

BLOCK-SIGNAL SYSTEM.

No. 882,553.

Specification of Letters Patent. Patented March 24, 1908.

Application filed March 9, 1905. Serial No. 249,178.

To all whom it may concern:

Be it known that I, FRED B. COREY, a citizen of the United States, residing at Schenectady, county of Schenectady, State of New York, have invented certain new and useful 5 Improvements in Block-Signal Systems, of which the following is a specification.

My invention relates to block signal systems, and is particularly applicable, though 10 not necessarily limited, to alternating-current systems. In many cases it is desirable to employ alternating current for operating such systems. Thus, for instance, in the case of an electric railway on which direct current is used for the driving motors, it is important that the leakage of power current from the rails should not affect the operation 15 of the signals. This end may be obtained by employing relays responsive only to alternating current and supplying alternating current 20 for the signal system.

My invention is particularly applicable to such a system, and its object is to provide a simple arrangement for obtaining what is 25 known as an overlap on block signal systems without the employment of any additional apparatus. I accomplish this result by supplying a coil of a track relay from the secondary of the same transformer which supplies 30 the track circuit of the block in advance, so that a train on a block, which short-circuits the secondary of the transformer supplying that block, will also act as a short-circuit on the coil of the relay of the block in the rear connected 35 to the same transformer.

My invention will best be understood by reference to the accompanying drawing which shows diagrammatically an alternating-current block signal system arranged in 40 accordance with my invention.

In the drawing R represents one of the track rails which is shown continuous so as to serve as a return conductor for the power current. The other rail is sectionalized in 45 the usual manner, portions of five sections R¹ to R⁵ being shown. Home and distant signals are shown at or near the entrance to each block, H' and D' representing respectively the home and distant signals at the entrance 50 to the block R¹.

The reference letters applied to the apparatus at the entrance to each block are distinguished by the numeral corresponding to the number of the block, as indicated by the 55 reference letter applied to the sectional rail.

In addition to the home and distant signals, the apparatus at the entrance to each block consists of operating mechanism for each signal, a source of current for the operating mechanism and a controlling relay. 60 Thus, I have indicated at the entrance to block R¹ a magnet winding h' as an operating mechanism for the home signal H'. The connections between the magnet winding h' and the signal H' are not shown, it being understood 65 that any well known type of operating mechanism may be employed, and that the magnet winding h' is purely diagrammatic, representing any well known form of signal driving mechanism. Similarly, the magnet winding d' represents the operating or driving means for the distant signal D'. B' represents a source of current for the operating coils h' and d', and r' represents an alternating-current relay controlling the circuits 70 of the operating mechanisms.

I have shown a relay of the type which comprises two relatively movable coils, one connected to the track circuit and the other supplied with alternating current of the same 80 frequency independently of the track circuits. When alternating current is flowing through both relay coils, a torque is produced between the two coils in one direction or the other, according to the relative direction of current-flow through the two coils; 85 which torque may be utilized to close the circuits of the operating mechanism for one or both signals. When the relay coil connected to the track circuit is short-circuited by a car or train on the block the relay has no 90 torque, and the circuits of both operating mechanisms are thereby opened, permitting the signals to go to danger by gravity. A direct current through one of the relay coils 95 can have no effect, since the other coil produces an alternating flux, so that the signal system is unaffected by the leakage of power current from the rails. L represents a line-wire extending along the track and supplied 100 with alternating current at a potential suitable for economic transmission. Transformers T¹, T², etc., are provided at the entrance to each block. The primary of each transformer is supplied from the line-wire L, 105 one terminal being connected to the line-wire and the other to the continuous rail R. The secondary of each transformer supplies both a track circuit and a coil of a relay of the block in the rear. Thus, for instance, it will 110

be seen that the movable coil a^3 of relay r^3 is connected across the track circuit of the block R^3 , while the stationary coil f^3 is connected to the secondary of the transformer 5 T^2 at the entrance of the block in advance. The secondary of this transformer T^2 is also connected through the reversing switch S^3 , which is operatively connected to the operating mechanism for the home signal H^3 , to the 10 farther end of the block R^2 : that is, the secondary of the transformer T^2 supplies the track circuit R^2 and also supplies one coil of the relay r^3 controlling the signals at the entrance of block R^3 .

15 The operation is then as follows: With a car or train in the block R^1 , as indicated at C, the relay coil a' is short-circuited and the contact arm carried thereby assumes the position shown, and is held there either by 20 gravity or by a spring. With the contact arm in the position shown, the circuits of both operating mechanisms h' and d' are opened and the signals H' and D' are held in danger position by their counter-weights, 25 showing the presence of a car in the block R' . The car C in the block R' short-circuits a part of the secondary winding of the transformer T' , and this short-circuit acts as a short-circuit on the entire secondary of the 30 transformer. Consequently the coil f^2 of the relay r^2 which is supplied from this secondary is deenergized and the coil a^2 is allowed to assume the position shown, opening the circuits of the operating mechanisms h^2 and 35 d^2 , and allowing the signals H^2 and D^2 to go to danger. The conditions at the entrance to block R^1 are thus repeated at the entrance to block R^2 . Thus the block R^2 serves as an overlap for the block R^1 , which is frequently desirable where the blocks are short, 40 and this result is obtained without the employment of any additional apparatus. The signal H^2 being in danger position, the reversing switch S^2 , which is operatively connected thereto is in the position shown. With the switch in this position the relative direction of current supplied to the block R^3 from the secondary of the transformer T^3 is such that the torque produced in the relay 45 r^3 is in a direction to move the contact arm toward the right, as shown. In this position the circuit of the operating mechanism h^3 is closed, while that of d^3 is opened. The home signal H^3 is consequently clear, while 50 the distant signal D^3 is at danger giving a caution indication in the usual manner. Since the home signal H^3 is in clear position, the reversing switch S^3 is in such a position that the relative direction of the current supplied to block 4 through the switch S^3 from the secondary of transformer T^4 is such that the direction of torque in the relay r^4 produces a movement of the contact arm toward 55 the left, so as to close the circuits of both operating mechanisms h^4 and d^4 , which hold

the signals of H^4 and D^4 at clear position. It will be observed that the reversing switches, while operating to reverse the relative connections of transformer and track circuit, do not disturb the connections from the transformer to the relay coil supplied therefrom. 70

It will be understood that the transformers are arranged as has been heretofore suggested in similar systems, with poor regulation, so that the short-circuit on the secondary does not produce an excessive flow 75 of primary current nor lower the potential on the line-wire L.

Although I have shown my invention applied to a system employing both home and distant signals, it will be understood that my invention is not limited to this particular arrangement. The system exactly as illustrated is applicable to systems employing only home signals, the only change being 80 the omission of the distant signals, the driving mechanism for the distant signals and the reversing switches. For the sake of simplicity I have shown my invention dia- 85 grammatically, and it will be understood that it is applicable to a system employing any suitable well known type of apparatus. Accordingly, I do not desire to limit myself to the particular construction and arrangement of parts here shown, but aim in the ap- 90 pended claims to cover all modifications which are within the scope of my invention. 95

What I claim as new, and desire to secure by Letters Patent of the United States, is,—

1. In a block signal system, separate 100 sources for supplying current to the track circuits of the several blocks, relays each comprising two coils, one connected to the rails of a block and the other connected to the same source of current that supplies the 105 track circuit of an adjacent block, and signals controlled by said relays.

2. In a block signal system, separate 110 sources for supplying current to the track circuits of the several blocks, relays each comprising two relatively-movable coils, one connected to the rails of a block and the other connected to the same source of current that supplies the track circuit of the 115 block in advance, and signals controlled by said relays.

3. In a block signal system, a source of alternating current extending along the roadway, transformers energized therefrom and each having its secondary connected to the track circuit of a block, relays each comprising two coils, one connected to the track 120 circuit of a block and the other connected to the secondary of the same transformer that supplies the track circuit of the block in advance, and signals controlled by said relays. 125

4. In a block signal system, a source of alternating current extending along the roadway, transformers energized therefrom and each having its secondary connected to 130

the track circuit of a block, relays each comprising two relatively-movable coils, one connected to the track circuit of a block and the other connected to the secondary of the same transformer that supplies the track circuit of the block in advance, and signals controlled by said relays.

5. In a block signal system, home and distant signals for each block, means for supplying current to the track circuits of the several blocks, relays each comprising two coils, one connected to the rails of a block and the other connected to the same source of current that supplies the track circuit of the block in advance, and a reversing switch operatively connected to each home signal and arranged when operated to reverse the relative direction of current flow through the preceding block without reversing the relative direction of flow through the relay coil supplied from the same source.

6. In a block signal system, home and distant signals, a source of alternating current extending along the roadway, transformers energized from said source and each having its secondary connected to the track circuit of a block, relays each comprising two coils, one connected to the rails of a block and the other connected to the secondary of the same transformer that supplies the circuit of the block in advance, and a reversing switch operatively connected to each home signal and arranged to reverse the relative connections of the track circuit of the preceding block and the transformer supplying said circuit without disturbing the connections from said transformer to the relay coil supplied therefrom.

7. In a block signal system, home and distant signals, a source of alternating current extending along the roadway, transformers energized from said source and each having its secondary connected to the track circuit of a block, relays each comprising two relatively movable coils, one connected to the rails of a block and the other connected to the secondary of the same transformer that supplies the track circuit of the block in advance, and a reversing switch operatively connected to each home signal and arranged to reverse the relative connections of the track circuit of the preceding block and the transformer supplying said circuit without disturbing the connections from said transformer to the relay coil supplied therefrom.

8. In a block signal system, home and distant signals, a source of alternating current extending along the roadway, transformers energized from said source and each having its secondary connected to the track circuit of a block, relays each comprising two relatively-movable coils, one connected to the rails of a block and the other connected to the secondary of the same transformer that supplies the track circuit of the block in ad-

vance, a reversing switch operatively connected to each home signal and arranged to reverse the relative connections of the track circuit of the block in the rear, and the transformer supplying said circuit without disturbing the connections from said transformer to the relay coil supplied therefrom, and a contact arm carried by the movable coil of each relay controlling both a home and a distant signal.

9. In a block signal system, separate sources for supplying current to the track circuits of the several blocks, relays each comprising two coöperating coils, one connected to the rails of a block and the other connected to the same source of current that supplies the track circuit of the block in advance, and signals controlled by said relays.

10. In a block signal system, signals for each block arranged to indicate danger, caution and clear, means for supplying current to the track circuits of the several blocks, relays each comprising two coöperating coils, one connected to the rails of a block and the other connected to the same source of current that supplies the track circuit of the block in advance, and a reversing switch operatively connected to the signal mechanism for each block arranged when operated to reverse the relative direction of current-flow through the preceding block without reversing the relative direction of flow through the relay coil supplied from the same source.

11. In a block signal system, a transformer having a secondary winding connected in circuit with the rails of a block and supplying voltage thereto, and a device controlling a signal for the preceding block connected in another circuit with said transformer, whereby the signal-controlling device is affected inductively through said transformer when said rails are short-circuited by a train.

12. In a block signal system, in combination with the rails of a block, a transformer for supplying voltage to said block, a device controlling a signal for the preceding block, and connections from different terminals of said transformer both to the rails of said block and to the signal-controlling device, whereby the signal-controlling device is affected inductively through said transformer by a train short-circuiting the rails of said block.

13. In a block signal system, the combination with track circuit sections and signals for such sections, and a source of energy connected at one end of each of said sections, a relay connected to the other end of each of said sections comprising a field energized from the source of energy energizing the next adjacent section, and an armature connected across the rails of the section in which it is included and capable of three functional positions, means for controlling the functional

positions of said armature, and means for making said signals give indications corresponding to the said three positions of said armature.

- 5 14. In a block signal system, the combination with insulated track circuit sections and signals for such sections, of means located at one end of each of said sections for creating a difference of potential between 10 the rails thereof, a relay connected at the other end of each of said sections comprising a member energized by a potential proportional to the difference of potential between the rails of the next adjacent section, and a 15 rotating member energized by the difference of potential between the rails of the section in which it is included and capable of three

functional positions, means for controlling said functional positions, means for operating one of said signals to the "proceed" position 20 by one of said functional positions of said armature, means for operating two of said signals to the "proceed" position by another functional position of said armature, and means for operating both of said signals 25 to the "stop" position by the third functional position of said armature.

In witness whereof I have hereunto set my hand this seventh day of March, 1905.

FRED B. COREY.
